LUDWIG HINKEL, OF NUEREMBERG, GERMANY, ASSIGNOR TO THE FIRM TESTA G. M.
B. H., OF FURTH, NEAR NUEREMBERG, BAVARIA, GERMANY.

METAL-TUBE PRESS.

Application filed March 10, 1928, Serial No. 260,671, and in Germany November 15, 1926.

The known method of pressing metal tubes from hot, sprayable metals and metallic alloys consists in employing a press ram with a projecting mandrel. The said mandrel perforates the work, which is then transformed into a tube by the penetration of the ram into the hole thus formed. The stroke of the press corresponds to the total length of the mandrel and ram, and is therefore of considerable length, and this of course means that the press must be of large dimensions.

The ram and mandrel are actuated by hydraulic pressure, which is applied suddenly and sets up a uniform rate of advance of the mandrel and ram. The sudden application of the pressure produces a very great strain on the machine, and in consequence of the resulting vibration militates against the precision of the pressing process. Moreover, in the case of hydraulic presses, their specific character renders satisfactory pressing of the material impossible.

The subject of the present application is a metal-tube press, which is of horizontal design and driven by mechanical means, and in which not only the ram, with mandrel, but also the member accommodating the work, is adapted to be displaced. Said member undergoes displacement during the perforating stage, while the ram moves during the pressing stage. In this way the stroke of the ram is considerably shortened; in fact by about one half, and consequently the actuation of the press, and also the press itself, is substantially simplified.

If, according to this invention, the known crank drive be employed to actuate the ram, the advantages of such drive can be fully utilized for the pressing stage. With this type of drive, the rate of advance of the ram increases from zero to a certain maximum, and then diminishes again to zero. The pressing stage therefore commences gradually and also terminates gradually, so that the vibrations of mass and material peculiar to the hydraulic drive, are prevented, and in addition, a satisfactory pressing-out of the material is obtained.

If the member accommodating the work is not moved, but only the ram and mandrel, the aforesaid advantages of the crank drive do not become manifest. In these circumstances, namely, the perforating stage oc-

cupies approximately the initial one third of the movement of the crank, and the pressing stage begins with a high rate of progression of the crank drive, which conditions are again accompanied by sudden application of the pressure and the concomitant vibration of the material or masses.

The invention will be clearly understood from the following description aided by the annexed drawing in which a typical example is shown and in which Figure 1 is a diagrammatic representation of a cross section of the press, while Figures 2 and 3 show the mandrel and member accommodating the work, in various positions.

Two horizontal sliding members 1, 2 are displaceably mounted in the frame of the machine. One of them houses the work carrier, press bush or member 3 accommodating the work 4, while the other forms the ram head holding the ram 5 with mandrel 6. The work carrier 1 is provided on each side with a stud 7 engaging in the curved slot 8 of a corresponding cam 9. When the cams 9 move, the studs 7 on the carrier 1 ride in the slots 8 of the cams 9, and thus set up a reciprocating movement of the carrier 1. The ram head 2 is connected, by means of a ball joint 10, with a connecting rod 11 engaging the pin 12 of a crank disc 13. The press is driven from a shaft 14 which actuates the cams 9, on the one hand, by means of the pinions 15, 16 and on the other, sets the crank disc 13 in motion through the pinions 18, 19.

In the first place, the work carrier member 3, with the matrix 20, is placed in the carrier 1, and is then charged with the solid blank 4 of the work, while the ram 5 and member 3 are in the positions shown in Figure 2, in which these two members of the press are in their extreme outward positions. On the driving mechanism of the press being thrown into the gear, the member 3 is first moved into its forward end position (Figure 1), before the crank disc 13 and the ram 5 have begun to move. This movement pushes the member 3 over the mandrel 6 of the ram 5; that is to say, the mandrel perforates the work 4. When the member 3 ceases to advance, the movement of the crank disc 13 and ram begins. The ram 5 penetrates the member 3 and forces the perforated work through the intermediate space between the mandrel 6

and the matrix 20, so that the tube is formed in known manner. This alternate movement of the member 3 and ram 5 is produced by designing and arranging the driving pinions 5 15, 16, 17 and 18, 19 accordingly.

The movement of the ram increases from zero to a maximum and then diminishes to zero again. The pressing stage therefore begins very gradually, a condition which 10 precludes, as far as possible, the vibrations of the masses and material, which have, hitherto seriously impaired the precision of the pressing process and the quality of the resulting tubes. In addition, a satisfactory 15 tension of the material is effected.

The process is naturally not restricted to pressing tubes, but is also applicable to pressing bars, sections, strip, wire and the like, in which case the mandrel and the movement of 20 the member 3 towards the latter can be omitted.

What I claim is:

1. A mechanical press for producing metal tubes, comprising a horizontally movable 25 ram, a crank operated driving means for operating said ram, a horizontally movable work carrying member, and means for transmitting motion to said member whereby the latter will move counter to said ram so that the work 30 carrier will be moved only during the per-

forating period and the ram will be moved only during the pressing action.

2. A mechanical tube press comprising in combination a horizontally movable work carrier, a horizontally movable ram comprising a preliminary piercing portion and an extruding portion, means for imparting motion to said carrier while said piercing portion pierces work mounted on said carrier and means for imparting motion to said ram after said piercing operation is complete whereby said ram will extrude said pierced work from said carrier.

3. A mechanical tube press comprising in combination a horizontally movable carrier, a tubular work carrier, having a restricted opening in one end, adapted to be mounted in said carrier, a horizontally movable ram comprising a preliminary piercing portion and an extruding portion, cam operated means for imparting motion to said carrier causing said piercing portion of said ram to pierce work mounted in said work carrier, and means for imparting motion to said ram after said piercing operation is complete whereby said ram will extrude said pierced work.

In testimony whereof I affix my signature.

LUDWIG HINKEL.
